UNITED STATES PATENT OFFICE

ARNO W. FOWLER, OF HIGHLAND, ILLINOIS

MOTOR CONTROL MECHANISM FOR ELECTRIC CLOCKS

Application filed November 8, 1929. Serial No. 405,833.

This invention relates to motor control mechanism for electric clocks; and an object of the invention is to provide improved equipment for controlling the operation of the electric motor by a device cooperatively associated with the clock spring mechanism and operated by the motor to stop the motor and operated by the clock spring mechanism to permit the motor to start.

Another object of the invention is to provide the improved frictional control device operated by the motor or frictionally stopping the motor automatically and as an incident to the completion of the winding operation and which is controlled by the clock spring, so as to permit the motor to operate to rewind the spring intermittently.

Various other objects and advantages will appear from the following description, reference being made to the accompanying drawings in which—

Fig. 1 is a vertical sectional view of a clock mechanism showing the present invention embodied therein.

Fig. 2 is a lateral side elevation of the clock mechanism.

Fig. 3 is a front side elevation of the clock.

Fig. 4 is an enlarged detail view showing the frictional control device for the motor in position to permit the motor to operate.

Fig. 5 is a detail view of the frictional control device in position to prevent operation of the motor.

The hour hand 1 and the minute hand 2 of this clock are operated by trains of gearing actuated by a large gear wheel 3. Operation of the gear wheel 3 is controlled by an escapement device 4. The escapement device 4 is associated with and controls a pinion 5 meshing with a gear wheel 6 attached to a shaft 7 having rigid thereon a pinion 8 meshing with a gear wheel 9 rigid on a shaft 10 having rigid thereon a pinion 11 meshing with a gear wheel 12 rigid on a shaft 13 rigid on which is a pinion 14 meshing with the gear 3. The minute hand 2 is attached to the shaft 13 and the hour hand 1 is attached to a sleeve 15 mounted for rotation on and about the shaft 13. A gear wheel 16 is rigid

with the sleeve 15 and loose with respect to the shaft 13 and is in mesh with a pinion 17 rotatively supported on a stub 18. The pinion 17 is rigid with a gear wheel 19, which is loose on the stub 18 and which meshes with and is rotated by a pinion 20 rigid on the shaft 13. By this familiar type of gearing, the hour hand 1 and the minute hand 2 of the clock are operated differentially in order correctly to indicate the time.

A spring drum 21 is rigid with the large gear wheel 3 and has attached thereto one end of a clock spring 22, the opposite end of which is attached to the shaft 23 on which the large gear wheel 3 is loosely supported. The spring 22 is an actuator for the time indicating mechanism and is energized by the motor driven mechanism. It is now clear that rotation of the shaft 23 in the proper direction will wind the spring 22. For, the gear wheel 3 is prevented from rotating with the shaft 23 by the escapement device and the gearing therefrom entraining the escapement device with said gear wheel 3.

The clock is equipped with an electric motor 24 to which electrical energy is admitted through the electric circuit wires 25 and 26. When the motor 24 is energized and operates, it rotates a shaft 27 having attached thereto a pinion 28 meshing with a gear wheel 29 attached to a rotary shaft 30. The rotary shaft 30 has attached thereto a pinion 31 meshing with a gear 32 attached to a rotary shaft 33. The rotary shaft 33 has attached thereto a pinion 34 meshing with a gear wheel 35 attached to a rotary shaft 36. The rotary shaft 36 and the gear wheel 35 are rigid with a pinion 37 meshing with a gear wheel 38 attached to the shaft 23. It is now clear that when the motor 24 operates, the shaft 23 will be rotated in a direction to wind and to tension the spring 22 and that rotation of the gear wheel 3 with the shaft 23 is prevented by the escapement mechanism. It is also clear that the escapement mechanism controls rotation of the gear wheel 3 by the spring 22 and that the motor and the gearing therefrom will prevent reverse rotation of the shaft 23, so that the

power and energy of the spring 22 is utilized to operate the hands 1 and 2 of the clock.

It is desirable to prevent the motor from winding the spring 22 beyond the desired tension and to coordinate the operation of the motor, so that the spring 22 will be wound automatically and as an incident to the operation of the invention. These desirable results are obtained by the embodiment of the invention shown.

The shaft 36 is a screw and has screwed thereon a pinion 39, which has a long periphery. This pinion 39 is in constant mesh with the gear wheel 3, so that, as the gear wheel 3 rotates, the pinion 39 is rotated thereby. Since the pinion 39 is screwed on the shaft 36, rotation of said pinion 39 by the gear wheel 3 will move the pinion 39 along the shaft 36 in one direction. It is apparent that rotation of the shaft 36 by the winding mechanism driven by the motor will move the pinion 39 along the shaft 36 in the opposite direction from which said pinion 39 is moved by rotation of the gear 3. Thus, when the motor is not operated, the gear wheel 3 operates to rotate the pinion 39 and the threads connecting said pinion 39 with the shaft 36 constitute means for moving the pinion 39 in one direction along said shaft 36. And when said shaft 36 is rotated by the motor driven winding gearing, the pinion 39 is held from rotation with said shaft 36 by engagement of said pinion 39 with the gear wheel 3. In this operation, the threads connecting the pinion 39 with the shaft 36 constitute means for moving the pinion 39 along the shaft 36 in the opposite direction from which said pinion 39 is moved when the gear wheel 3 rotates said pinion 39.

A lever 40 is supported by the shaft 30 for pivotal swinging and lateral oscillating movements. In order to support said lever 40 for these pivotal swinging and lateral oscillating movements, said lever 40 is provided with a large hole 41 through which the shaft 30 extends. The upper end of the lever 40 has arms 42 embracing between them the shaft 36. The arrangement of the lever 40 with respect to the pinion 39 is such that said pinion 39 is moved along the shaft 36 in a direction away from said lever 40 when said pinion 39 is rotated by the gear wheel 3; and when the shaft 36 is rotated by the winding gearing, the pinion 39 is moved along said shaft 36 in a direction toward and into engaging contact with the bifurcated end of said lever 40. When the pinion 39 is moved by the winding mechanism operated by the motor, said pinion 39 contacts with and moves the lever 40 toward the gear wheel 29.

The lower end of the lever 40 is rebent to form an arm 43 spaced from the lever 40, so as to embrace a peripheral portion of the gear wheel 29 between the arm 43 and the lever 40. The lever 40 has attached thereto a friction

block 44, and a similar friction block 45 is attached to the arm 43. The gear wheel 29 is between the blocks 44 and 45. The block 44 is closer to the shaft 30 than the block 45. These blocks 44 and 45 are of such length and arrangement that when the bifurcated end of the lever 40 is moved toward the gear wheel 29, said blocks will frictionally engage and grip the gear wheel 29 with sufficient pressure and force to stop rotation of said pinion 39, and thereby stop the motor. Thus, these parts are coordinated and arranged so that when the spring 22 is wound to the desired extent, the winding mechanism comprising the motor will be stopped positively automatically and as an incident to the completion of the winding operation.

In operation, the spring is wound with sufficient tension to operate the hands 1 and 2 of the clock. Differential operation of these hands is effected by the trains of gearing described, which trains of gearing are operated by the gear wheel 3 under control of the escapement mechanism. Operation of the gear wheel 3 causes the threads engaging the pinion 39 with the shaft 36 to move the pinion 39 along the shaft 36 in a direction away from the lever 40. When the pinion 39 moves away from the lever 40 a distance sufficient to release frictional engagement of the blocks 44 and 45 with the gear wheel 29, there is no restraint preventing operation of the motor. When the restraint preventing operation of the motor is ended, the motor, which is constantly energized, begins to operate automatically. Operation of the motor through the train of gearing, comprising the pinion 28, the gear wheel 29, the pinion 31, the gear wheel 32, the pinion 34, the gear wheel 35, the pinion 37, and the gear wheel 38, rotates the shaft 23 and thereby winds the spring 22. This gearing also rotates the shaft 36, thereby moving the pinion 39 along said shaft in a direction and to an extent to cause the lever 40 to operate the friction blocks 44 and 45 and to grip in frictional engagement with the gear wheel 29 effectively to stop the motor.

It is now clear that this invention obtains all of its intended objects in a highly efficient and satisfactory manner. The construction, arrangement and relationship of the elements comprising the invention may be widely varied without departure from the nature and principle of the invention, and I contemplate such variations as may be found desirable and do not restrict myself unessentially in any respects, but what I claim and desire to secure by Letters Patent is:

1. Mechanism of the character described comprising a rotary gear wheel, a shaft on which said gear wheel is rotatively supported, a spring having one end attached to said shaft and the opposite end attached to said gear wheel for rotating said gear wheel while said shaft remains stationary, a motor,

a rotary threaded shaft, mechanism for rotating said threaded shaft by said motor, mechanism for rotating said first shaft by said threaded shaft to wind said spring, and a 5 device operated by said threaded shaft for stopping operation of said motor.

2. Mechanism of the character described comprising a rotary gear wheel, a shaft on which said gear wheel is rotatively supported, 10 a spring having one end attached to said shaft and the opposite end attached to said gear wheel for rotating said gear wheel while said shaft remains stationary, a motor, a rotary threaded shaft, mechanism for rotating 15 said threaded shaft by said motor, mechanism for rotating said first shaft by said threaded shaft to wind said spring, a device operated by said threaded shaft for stopping operation of said motor, and means operated 20 by said gear wheel for screwing said device along said threaded shaft to position to permit operation of said motor.

3. Mechanism of the character described comprising a rotary threaded shaft, a motor, 25 a train of pinions and gear wheels for rotating said threaded shaft from said motor, an element screwed on said threaded shaft, means for holding said element from rotating with said threaded shaft to cause said threaded 30 shaft to move said element along said threaded shaft when said shaft is rotated, and a friction device engaging one of said gear wheels and arranged to move to position to permit said gear wheel to rotate and 35 being engaged and operated by said element to obtain frictional engagement with and prevent rotation of said gear wheel by said motor.

4. Mechanism of the character described 40 comprising an electric motor, a shaft, a gear wheel mounted on said shaft, means for rotating said gear wheel by said motor, a threaded shaft, mechanism driven by said gear wheel for rotating said threaded shaft, 45 a lever supported on said first shaft, friction devices supported by said lever for frictionally engaging said gear wheel, and a device operated by said threaded shaft for operating said lever into frictional engagement with 50 said gear wheel.

5. Mechanism of the character described comprising an electric motor, a shaft, a gear wheel mounted on said shaft, means for rotating said gear wheel by said motor, a threaded shaft, mechanism driven by said gear wheel for rotating said threaded shaft, 55 a lever supported on said first shaft, friction devices supported by said lever for frictionally engaging said gear wheel, a device operated by said threaded shaft for operating said lever into frictional engagement with said gear wheel, and mechanism for moving said device along said threaded shaft to position to permit said lever to release said gear wheel.

6. Mechanism of the character described

comprising an electric motor, a shaft, a gear wheel supported by said shaft and rotated by said motor, a threaded shaft, mechanism driven by said gear wheel for rotating said threaded shaft, a lever mounted on said first shaft, means supported and operated by said lever for engaging and preventing operation of said gear wheel and stopping said motor, and a device operated by said threaded shaft for operating said lever to position to prevent operation of said gear wheel.

7. Mechanism of the character described comprising an electric motor, a shaft, a gear wheel supported by said shaft and rotated by said motor, a threaded shaft, mechanism driven by said gear wheel for rotating said threaded shaft, a lever mounted on said first shaft, means supported and operated by said lever for engaging and preventing operation of said gear wheel and stopping said motor, a device operated by said threaded shaft for operating said lever to a position to prevent operation of said gear wheel, and mechanism for moving said device to position to permit movement of said lever to position to permit rotation of said gear wheel.

8. The combination with an electric motor, a gear wheel rotated by said motor, and a shaft supporting said gear wheel of a friction device supported by said shaft for engaging and preventing operation of said gear wheel by said motor and thereby preventing operation of said motor, and mechanism operated by said gear wheel for operating said device to a position to prevent operation of said gear wheel.

9. The combination with an electric motor, a gear wheel rotated by said motor, and a shaft supporting said gear wheel, of a friction device supported by said shaft for engaging and preventing operation of said gear wheel by said motor and thereby preventing operation of said motor, mechanism operated by said gear wheel for operating said device to a position to prevent operation of said gear wheel, and means for moving said device to position to permit operation of said gear wheel.

10. Mechanism of the character described comprising an electric motor, a gear wheel operative by said motor, a shaft supporting said gear wheel mechanism driven by said gear wheel, and a device supported by said shaft and operated by said mechanism for 115 frictionally gripping and preventing operation of said gear wheel and thereby preventing operation of said motor.

11. Mechanism of the character described comprising an electric motor, a gear wheel 125 rotative by said motor, a shaft supporting said gear wheel an actuator, mechanism operated by said gear wheel for energizing said actuator, a device supported by said shaft for frictionally engaging and preventing op-

eration of said gear wheel and thereby preventing operation of said motor, and means operated by said mechanism for moving said device to a position to prevent operation of 5 said gear wheel by said motor.

12. Mechanism of the character described comprising an electric motor, a gear wheel rotative by said motor, a shaft supporting said gear wheel an actuator, mechanism operated 10 by said gear wheel for energizing said actuator, a device supported by said shaft for frictionally engaging and preventing operation of said gear wheel and thereby preventing operation of said motor, means operated 15 by said mechanism for moving said device to a position to prevent operation of said gear wheel by said motor, and means operated by said actuator for moving said device to position to permit rotation of said gear wheel by 20 said motor.

13. Mechanism of the character described comprising an electric motor, a shaft, a gear wheel mounted on said shaft, means for rotating said gear wheel by said motor, an additional shaft, an actuator supported by said additional shaft, mechanism operated by said gear wheel for rotating said additional shaft and thereby energizing said actuator, a device supported by said first shaft for frictionally 25 engaging and preventing operation of 30 said gear wheel and thereby preventing operation of said motor, and means operated by said mechanism for moving said device to a position to prevent operation of said 35 gear wheel by said motor when said actuator is sufficiently energized.

14. Mechanism of the character described comprising an electric motor, a shaft, a gear wheel supported by said shaft, means for rotating said gear wheel by said motor, a threaded shaft, mechanism driven by said gear wheel for rotating said threaded shaft, a lever supported by said first shaft, friction devices supported by said lever for frictionally 40 engaging said gear wheel, and a device operated by said threaded shaft for moving said lever into frictional engagement with said gear wheel.

15. Mechanism of the character described 45 comprising an electric motor, a shaft, a gear wheel supported by said shaft, means for rotating said gear wheel by said motor, an additional shaft, an actuator mounted on said additional shaft, mechanism operated by 50 said gear wheel for energizing said actuator, a device supported by said first shaft for frictionally engaging and preventing operation of said gear wheel and thereby preventing operation of said motor, means operated 55 by said mechanism for moving said device to a position to prevent operation of said gear wheel by said motor, and means operated by said actuator for moving said first named 60 means to position to permit said device to release said gear wheel.

16. Mechanism of the character described comprising an electric motor, a gear wheel rotative by said motor, a shaft, an actuator mounted on said shaft, a second shaft, means for rotating said second shaft by said gear wheel, means for rotating said first shaft by 70 said second shaft, and a device supported by said second shaft for frictionally engaging and preventing operation of said gear wheel and thereby preventing operation of said motor. 75

17. Mechanism of the character described comprising an electric motor, a gear wheel rotative by said motor, a shaft, an actuator mounted on said shaft, a second shaft, means for rotating said second shaft by said gear wheel, means for rotating said first shaft by said second shaft, a device supported by said second shaft for frictionally engaging and preventing operation of said gear wheel and thereby preventing operation of said motor, and means operated by said shaft for causing said device to permit operation of said motor. 80

18. Mechanism of the character described comprising an electric motor, a shaft, a gear wheel mounted on said shaft, a second shaft, a gear wheel mounted on said second shaft, means for rotating said first gear wheel by said motor, a threaded shaft spaced from said first and second shafts, mechanism driven by said first gear wheel for rotating said threaded shaft, a lever, friction means supported by said lever for frictionally engaging said first gear wheel, and a device operated by said threaded shaft for operating said lever to position to engage said friction means with said first gear wheel. 90

19. Mechanism of the character described comprising an electric motor, a gear wheel, a shaft supporting said gear wheel, mechanism for rotating said gear wheel by said motor, a threaded shaft, mechanism driven by said gear wheel for rotating said threaded shaft, a third shaft, a gear wheel on said third shaft, a device mounted on and operated by said threaded shaft and engaging said second gear wheel, and a friction element operated by said device to engage said first gear wheel. 105

20. Mechanism of the character described comprising an electric motor, a gear wheel operative by said motor, a shaft, a second shaft, mechanism driven by said gear wheel for rotating said second shaft, a threaded shaft driven by said mechanism, friction means for engaging said first gear wheel, and a device mounted on and operated by said threaded shaft and engaging said second gear wheel for operating said friction means into frictional engagement with said first gear wheel to prevent operation of said motor. 110
